ABSTRACT

A Water Vehicle having a motorcycle-type body and supported on three pontoons detachably connected to said body, and including rudder steering operable by handlebars wherein a braking mechanism is connected to the steering mechanism to provide braking by moving the rudders in opposite directions.

described depression of brake pedals 37 affects the operation of rudders 38.

Turning now to a description of the preferred detachable connection between support members 32 and pontoons 26 (also preferred and illustrated for the connection between handlebar column 25 and pontoon 27), with specific reference to FIGS. 5 and 6, a support member 32, shown in dotted lines, is illustrated. Each support member 32 has a foot portion 39 which may be inserted upon attachment into female opening 40 of a pontoon 26. In connecting a support member 32 to a pontoon 26 the foot portion 39 is inserted into female opening 40 and moved under cover plate 41 so as to be clear of spring operated plunger mechanism 42. Spring operated plunger mechanism 42 is depressed to allow foot portion 39 to assume said position and when foot portion 39 is out of the way spring operated plunger mechanism 42 will rise in opening 40 to prevent extraction of foot portion 39 and thereby make a firm connection. To undo the connection it is only necessary to depress spring operated plunger mechanism 42. Mechanical stop 43 retains spring operated plunger mechanism 42. The water vehicle of the present invention will normally be transported to and from water without the pontoons attached, and thus it is a highly important feature of the present invention to provide an efficient attachment and detachment mechanism for the pontoons.

FIGS. 7 and 8 illustrate in detail one preferred means of attaching cross members 30 and 31 to pontoons 26. In FIGS. 7 and 8 the cross member is designated by reference numeral 43 and is shown in dotted lines. As shown a hinged cover plate 44 is attached to pontoon 26 and hinged cover plate 44 may be closed after cross member 43 is inserted in place and secured to pontoon 26, as by screw member 45.

FIG. 9 illustrates in a detailed fashion handlebar column 25 at its detachable connection with pontoon 27 and the construction of yolk 34 to show the manner of obtaining longitudinal movement of rod members 35 in opposite directions when the handlebar shaft 33 is turned.

FIG. 10 shows in detail the construction of rudder mechanism 36. The rearward ends of rod members 35 are connected as shown to lever arms 46, which are the upper ends of rotatably mounted rudders 38. Because of the illustrated arrangement of lever arms 46, it will be readily apparent to those skilled in the art that equal and opposite longitudinal movement of rod members 35, as provided through yolk 34, will cause rudders 38 to act together as a pair in steering the water vehicle of the present invention.

FIG. 11 illustrates in detail the braking mechanism of the present invention. Shown is brake pedal 37 rotatably mounted on fixed pin 47. Attachment 48 allows rod members 35 to have normal longitudinal movement for steering. Depression of brake pedal 37, it will be readily apparent to those skilled in the art, moves attachment 48 to effectively shorten rod member 35. In the present invention the mechanism illustrated by FIG. 11 is operable on both rod members 35 together and thus upon depression of brake pedal 37 both rod members 35 are effectively shortened, which, as can be seen most clearly from FIG. 10, has the effect of turning both rudders 38 outwardly, which will provide a braking action.

Various changes in the embodiment herein chosen for purposes of illustration in the drawings will readily appear to persons skilled in the art having regard for the disclosure herein. To the extent that such modifications and variations do not depart from the spirit of the invention, they are intended to be included within the scope thereof which is not limited to the embodiment specifically illustrated, but rather only to a fair interpretation of the following claims.

10 Having fully described the invention in such manner as to enable those skilled in the art to understand and practice the same, I claim:

15 1. In a water vehicle, the combination comprising: a motorcycle-type body portion, including frontally located handlebars, a rearwardly located seat portion, and engine means positioned therebetween; a pair of longitudinal pontoons, one of said pair being located parallel to and adjacent sidewardly of said motorcycle-type body portion and the other of said pair being symmetrically located on the other side of said motorcycle-type body portion; a third pontoon located frontally and centrally with respect to said motorcycle-type body portion and fixed parallel to said pair of pontoons; rudder means operable by movement of said handlebars; and connection means between said motorcycle-type body portion and said pontoons constructed and arranged to provide a detachable connection therebetween;

20 30 a. Including steering means comprising: a pair of rearwardly located rudders; a pair of rod members connected to said handlebars in such manner that turning of said handlebars causes longitudinal movement of said rod members in opposite directions to each other; a said rudder being connected to a said rod member in such manner as to cause said pair of rudders to rotate in the same direction upon operation of said handlebars; and

b. Including braking means constructed and arranged to rotate said pair of rudders in opposite direction when said braking means is activated.

25 40 2. The water vehicle of claim 1 wherein said braking means comprises pedal means constructed and arranged to effectively shorten said rod members upon activation of said pedal means.

30 45 3. In a water vehicle, the combination comprising: a motorcycle-type body portion, including frontally located handlebars, a rearwardly located seat portion, and engine means positioned therebetween; a pair of longitudinal pontoons, one of said pair being located parallel to and adjacent sidewardly of said motorcycle-type body portion and the other of said pair being symmetrically located on the other side of said motorcycle-type body portion; a third pontoon located frontally and centrally with respect to said motorcycle-type body portion and fixed parallel to said pair of pontoons; rudder means operable by movement of said handlebars; and connection means between said motorcycle-type body portion and said pontoons constructed and arranged to provide a detachable connection therebetween;

35 50 55 60 65 a. Wherein said connection means between said motorcycle-type body portion and said pontoons comprises: an attachment member between said motorcycle-type body portion and said pontoon, the lower end of said attachment member having a male foot portion adapted to fit into a female structure in said pontoon, said female structure contain-

ing a mechanical locking device constructed and arranged to hold said male foot portion in said pontoon.

4. The water vehicle of claim 3 wherein said mechanical locking member is spring operated.

5. In a water vehicle, the combination comprising: a motorcycle-type body portion, including frontally located handlebars, a rearwardly located seat portion, and engine means positioned therebetween; a pair of longitudinal pontoons, one of said pair being located parallel to and adjacent sidewardly of said motorcycle-type body portion and the other of said pair being symmetrically located on the other side of said motorcycle-type body portion; a third pontoon located frontally and centrally with respect to said motorcycle-type body portion and fixed parallel to said pair of pontoons; rudder means operable by movement of said handlebars; and connection means between said motorcycle-type body portion and said pontoons constructed and arranged to provide a detachable connection therebetween,

a. Including steering means comprising: a pair of rearwardly located rudders; a pair of substantially noncompressible rod members connected to said handlebars in such manner that turning of said handlebars causes longitudinal movement of said rod

5

members in opposite directions to each other; a said rudder being connected to a said rod member in such manner as to cause said pair of rudders to rotate in the same direction upon operation of said handlebars.

10

6. In a water vehicle, the combination comprising: a longitudinal motorcycle-type body portion, including frontally located handlebars, a rearwardly located seat portion, and engine means positioned therebetween; a pair of longitudinal pontoons, each of said pair having its longest longitudinal axis located parallel to and adjacent sidewardly of said motorcycle-type body portion, one of said pairs being located on one side of said motorcycle-type body portion and the other of said pair being symmetrically located on the other side of said motorcycle-type body portion; a third pontoon located frontally and centrally with respect to said motorcycle-type body portion and having its longest longitudinal axis fixed parallel to the said longest longitudinal axes of said pair of pontoons; rudder means operable by movement of said handlebars; and connection means between said motorcycle-type body portion and said pontoons constructed and arranged to provide a detachable connection therebetween.
